UNITED STATES PATENT OFFICE.

OSCAR H. HASSELBAUM, OF FRESNO, CALIFORNIA.

TIMER FOR INTERNAL-COMBUSTION ENGINES.

1,347,370.

Specification of Letters Patent. Patented July 20, 1920.

Application filed May 15, 1918. Serial No. 234,639.

To all whom it may concern:

Be it known that I, OSCAR H. HASSELBAUM, a citizen of the United States of America, residing at Fresno, in the county 5 of Fresno and State of California, have invented new and useful Improvements in Timers for Internal-Combustion Engines, of which the following is a specification.

The invention refers to attachments for 10 internal combustion engines, and particularly to those kinds of engines which are used with auto vehicles.

The principal object of the invention is to provide a timer in which the use of oil will 15 be unnecessary.

A further object is to provide a timer which will give a long continuous spark at the spark plug, so that all of the gas may be ignited and maximum power of the engine 20 obtained.

A still further object is to provide a timer having a wiping contact, thereby obtaining a greater area of contact than could be obtained with a timer having a roller.

25 A still further object is to provide the timer, the moving parts of which are copper gauze brushes, arranged in tandem as regards their travel around the stationary portion of the timer.

30 A still further object is to provide a timer which is simple in construction, durable and effective in operation, and inexpensive to manufacture.

Still further and other objects will appear 35 in the following detailed description.

To the exact construction in which it is shown and described, the invention is not to be restricted. The right is reserved to make such changes or alterations as the actual 40 reduction to practice may demand, provided such changes or alterations are comprehended in spirit by the annexed claim.

The same numerals of reference designate the same parts throughout the several figures 45 of the drawings, wherein:

Figure 1 is an elevational view of the improved timer looking at the inside thereof,

Fig. 2 is a section on the line 2—2 of Fig. 1,

Fig. 3 is a section on the line 3—3 of Fig. 1.

50 Referring to the drawings, there is shown, a hollow casing 1, the portion 2 of which is cylindrical in shape. On the interior of the cylindrical portion 2, there is held a ring 3 made of some insulating material, prefer-

ably fiber. On the inner periphery of the 55 ring 3, there are inset the segments 4, all these being an equal angular distance apart.

Radially projecting from the outside of the cylindrical portion 2 of the casing, there are binding posts 5, each one of which connects with one of the segments 4, the binding posts passing through the wall of the portion 2 from which they are insulated by the fiber bushings 6. Each binding post carries a nut 7 which screws down against the 60 attendant bushing 6 and, connecting with the attendant segment 4, the binding posts thus serve to hold the ring 3 in position in the casing 1, since the binding posts fixedly connect with the segments which are inset 65 in the ring.

Each binding post is further provided with a nut 8 for effecting the attachment of the lead from the induction coil to the binding post.

70 Coöoperating with the segments 4, there is a brush holder 9 which is secured on and turned by a cam shaft 10. This brush holder carries side by side, two brushes 11 which are made preferably of copper gauze and are 75 held in contact with the ring 3 and the segments 4 by springs 12.

In the use of the invention, the cam shaft 10 turns the brush holder 9 and its two brushes are thereby wiped over the inner 80 periphery of the ring 3 and over the segments 4 in turn, the segments being made of bronze, brass or copper, preferably the former. The copper brushes thus wiping over the bronze segments insure a clean contacting surface, as the brushes sliding over the ring keep a clean path before them. Should there be any dirt, the first brush will wipe it out of the way and allow a clean contact for the second brush.

85 The employment of two brushes, throws the sparking resulting from breaking the circuit on to the second brush, since the first brush leaves the segment first, thereby leaving the circuit closed through the second 90 brush until the latter leaves the segment. All the sparking resulting therefore from breaking the circuit is thrown on the second brush.

95 The particular arrangement does not require the use of oil to keep the timer in condition, since the employment of copper brushes running on bronze segments and a fiber ring does not produce undue friction,

and these two metals being relatively soft, they may be rubbed one over the other without the result of any scratching.

The particular arrangement for having the brushes held in the holder so that they project radially in making contacts with the ring and with the segments, affords means for keeping the brushes in contact with the segments by centrifugal force when the cam shaft is running. Thus the brushes will maintain fairly good contact even though the springs pressing upon them may become weakened. This arrangement also provides for obtaining increased contact pressure when the cam shaft is running at high speed.

From the foregoing description taken in connection with the accompanying drawings, the construction and advantages of the invention are apparent, and further description is therefore unnecessary.

The invention having been described, what is claimed as new and useful is:

In a spark timing-device, the combination of a casing, an insulating ring carried in the casing, contact segments inset in the inner periphery of said ring, a rotating shaft having a portion within the casing and being concentrically disposed with reference to said ring, a brush holder within the casing and carried by and rotated by said shaft, and a pair of yieldably mounted brushes carried in the said holder and disposed side by side, the brushes bearing upon the insulating ring and the segments but being so positioned that one leads the other in the direction in which they move, as herein shown and specified.

In testimony whereof I affix my signature.

OSCAR H. HASSELBAUM.
